(57) **CLAIM**

The ornamental design for a beverage container closure, as shown and described.

DESCRIPTION

FIG. 1 is a perspective view of a beverage container closure showing the design.

FIG. 2 is a side view of the beverage container closure of FIG. 1.

FIG. 3 is another side view of the beverage container closure of FIG. 1.

FIG. 4 is another side view of the beverage container closure of FIG. 1.

FIG. 5 is another side view of the beverage container closure of FIG. 1.

FIG. 6 is a top plan view of the beverage container closure of FIG. 1.

FIG. 7 is a bottom plan view of the beverage container closure of FIG. 1; and,

FIG. 8 is another perspective view of the beverage container closure of FIG. 1.

The dashed lines in the drawings illustrate portions of the beverage container closure that form no part of the claimed design. The shading lines shown in the drawings represent the approximate three dimensional contour of the claimed design and are not intended to indicate surface decoration. The dot-dash-dot boundary lines in FIGS. 1 and 6 depict the boundary of the claim and form no part thereof.

1 Claim, 5 Drawing Sheets
